APPARATUS FOR BEVELING FELT
PROTECTIVE PADSJohn F. Piller, Chicago, Ill., assignor to The Scholl
Mfg. Co., Inc., Chicago, Ill., a corporation of
New York

Application November 9, 1949, Serial No. 126,409

6 Claims. (Cl. 164—71)

1

This invention relates to improvements in methods and apparatus particularly adapted to bevel soft felt protective pads for corns or the like.

Heretofore the top and bottom faces of protective pads which have been produced for the general trade have usually been parallel. It has been found, however, that where the outer surface of the felt of the pad is uniformly beveled along the periphery thereof, that undesirable pressure between the pad and foot or toe of the user is greatly minimized, with the result that a beveled felt protective pad is much more comfortable than a pad having parallel top and bottom surfaces. While the beveled protective pad has been found to be far superior to the pads now on the market, due to the increased comfort to the wearer of the pad, beveled pads have never been supplied in commercial quantities to any great extent due to the fact that it has not heretofore been possible to bevel the soft felt of the pad by machine, such pads which have formerly been produced being beveled by hand, making them extremely costly to manufacture.

One object of the present invention is to remedy the foregoing difficulties by providing a novel and improved method and apparatus for efficiently and inexpensively beveling soft felt protective pads for corns or the like.

A further object of my invention is to provide a novel method for beveling soft felt protective pads in a more efficient and facile manner than formerly by cutting the outer and top surfaces of the pad at the desired angle of the bevel with a high speed knife like rotary cutting action movable transversely of the top surface of the pad and following the contour of the periphery of the pad.

A further and more specific object of my invention is to provide a new and improved form of apparatus for beveling the top and outer surfaces of soft felt protective pads of various desired shapes by providing a rotary knife rotatably driven at a high rate of speed with its cutting edge inclined at substantially the angle of the desired bevel of the pad and moving transversely of the top of the pad and by providing means for feeding this cutter along the pad in the path of the periphery thereof.

A further and more specific object of my invention is to provide an apparatus for beveling soft protective pads in a more efficient and facile manner than formerly having a high speed rotary knife cutter with its cutting edge positionable in the plane of the desired bevel of the pad and

2

having cam means bodily moving the cutter in the path of the periphery of the pad to be beveled.

These and other objects of my invention will appear from time to time as the following specification proceeds and with reference to the accompanying drawings wherein:

Figure 1 is a view in side elevation of a beveling apparatus constructed in accordance with my invention;

Figure 2 is a front end view of the apparatus shown in Figure 1;

Figure 3 is an enlarged fragmentary detail plan view of the work supporting table for the pad to be beveled;

Figure 4 is a fragmentary side view of the apparatus looking at the opposite side thereof from Figure 1;

Figure 5 is an enlarged fragmentary horizontal sectional view taken substantially along line V—V of Figure 2;

Figure 6 is a fragmentary transverse sectional view taken through the beveling apparatus and substantially along line VI—VI of Figure 5;

Figure 7 is a fragmentary sectional view taken substantially along line VII—VII of Figure 6;

Figure 8 is a fragmentary bottom plan view looking toward the cutting disk and support from the bottom thereof, substantially along line VIII—VIII of Figure 6;

Figure 9 is a fragmentary horizontal sectional view taken substantially along line IX—IX of Figure 6;

Figure 10 is a fragmentary sectional view taken through the rotary disk cutter substantially along line X—X of Figure 6; and

Figure 11 is a perspective view of a corn pad, beveled in accordance with my invention.

Figures 1 and 2 of the drawings show a beveling machine 10 constructed in accordance with my invention, mounted on the top of a bench or table 11. The table 11 may be of any desired form and is herein shown as being a well known form of table of the work bench type having a foot lever 12 transversely pivoted thereto and arranged to control raising and lowering of a rotary knife 14 to and away from the work, to form a beveled pad 15, as shown in Figure 11, from a felt having parallel top and bottom sides, as will hereinafter more clearly appear as this specification proceeds.

The beveling machine 10 includes a base 16 suitably mounted on the top of the table or bench 11 and having a column 19 mounted thereon and projecting upwardly therefrom. An

overhanging or outboard support member 20 is mounted on the column 19 adjacent its upper end, and projects outwardly therefrom and forms a support for the knife 14 and the mechanism for driving and feeding said knife. The outboard support 20 has an outer end portion 21, the inside of which may be substantially cylindrical, open to the inside thereof, in which is slidably guided a post 23. The post 23 has rack teeth 24 cut on its rear face and also has a support plate 25 secured to its lower end and extending outwardly therefrom. The support plate 25 has a vertically extending motor support 26 at its outer end, to which is secured a drive motor 27 having a vertical armature shaft 28 and forming a drive for the rotary knife 14, and also forming a drive for the means for feeding said knife in a path conforming to the contour of the pad to be beveled.

The post 23 is vertically adjusted with respect to the cylindrical portion 21 of the outboard support 20 by means of a pinion 29 on a shaft 30 and meshing with the rack teeth 24. Said pinion may be turned by a hand wheel 31 on an outer end of shaft 30. Vertical movement of the post 23 and cutter 14 is limited by means of two vertically spaced knurled nuts 32—32. The nuts 32—32 are threaded on a vertical threaded shaft 33 in spaced apart relation with respect to each other and are adapted to engage opposite sides of a lug 34, projecting laterally from the outboard support 20 and having the threaded shaft 33 passing therethrough. The shaft 33 is mounted at its lower end on a strap 35 secured to the post 23, for vertical movement therewith.

When the cutter disk 14 has been set to the proper cutting angle and height, it may quickly be moved into or out of engagement with the felt by means of the foot lever 12. The foot lever 12, as herein shown, has a link 39 pivotally connected thereto intermediate its end and extending upwardly therefrom. The link 39 is herein shown as being connected to a parallel upwardly extending link 40 by means of a coupling member 41, affording a means for adjusting the length of the resultant link formed by said connected links. A tension spring 43 connected between the bottom of the top of the table 11 and the coupling 41 is provided to urge the foot lever 12 into an upwardly extended position and raise the knife 14 above the work when foot pressure is relieved from the pedal of said lever. The upper end of the link 40 is pivotally connected to one lever arm of a bell crank 45, transversely pivoted to the outboard support 20 on a pivotal pin 46, projecting outwardly therefrom. The other lever arm of the bell crank 45 depends from the pivotal pin 46 and has a link 47 pivoted thereto, connecting said bell crank to a lever arm 49, secured to the shaft 30. Depression of the foot lever 12 will thus pivot the shaft 30 and pinion 29 in a direction, which in Figure 1 is a clockwise direction, and move knife 14 downwardly into engagement with the work.

The support plate 25 is herein shown as being suitably secured to and projecting outwardly from the post 23, adjacent the lower end thereof. The plate 25 has three radially spaced slots 53—53 extending therethrough from the top to the bottom thereof and intermediate the ends of said plate and forming a means for adjustably mounting a support member 54 on the underside thereof, as by machine screws 55—55 extending through said slots and threaded within said support member (Figures 5 and 6). The support

member 54 forms a support for a spindle 56 mounted therein and depending therefrom. The spindle 56 has a reduced upper end portion 57 extending through said support member and partially through the support plate 25, and detachably secured thereto as by a set screw 58. The spindle 56 has a sleeve 60 mounted thereon having a rectangularly flanged lower portion 61. The sleeve 60 is free to rotate about the spindle 56 and is held in engagement therewith by means of a disk 63 mounted on a reduced lower end portion of said spindle and abutting the bottom of the flange 61. The disk 63 is herein shown as being held to the reduced lower end portion of said shaft by means of a cam 64 having a hollow central portion encircling said shaft, and secured thereto as by a machine screw 66 threaded in the bottom of said shaft. The bottom of the rectangular flange 61 has two parallel gibs 67—67 depending therefrom and extending along opposite sides thereof and forming a slideable guide for a tool support 69. Two parallel spaced retaining strips 70—70 are suitably secured to the bottoms of said gibs and extend therealong and inwardly therefrom along the underside of the tool support 69 to slidably support said tool support on the bottom of said flange.

The tool support 69 as shown in Figures 6, 7, 8 and 9 comprises a flat plate 73 engaged by the retaining strips 70—70 and having an inner cut-away portion 74 within which the cam 64 extends. The plate 73 is herein shown as having a depending block 75 secured to the underside thereof as by machine screws 76—76. The block 75 has an inner upper shouldered portion 77 having a cam follower 79 rotatably mounted thereon for engagement with the outer face of the cam 64.

The follower 79 is held in engagement with the cam 64 by two tension springs 81—81 (Figures 8 and 9). Said springs are secured at one of their ends to the outer end portions of a yoke-like portion 83 of the support plate 73 and at their opposite ends to machine screws 84—84 threaded within opposite outer sides of the flange 61. Rotation of the sleeve 60 will thus rotatably drive the tool support 69, and where the cam 64 is of an irregular or oval formation said tool support will rectilinearly move along the gibs 67—67 as it is rotatably driven by the sleeve 60, following the contour of said cam, which may be in the form of the periphery of the corn pad being beveled. It is obvious that where the corn pads are circular, as shown in Figure 11, the cam 64 will be of a circular formation and that with such a cam there will be no translational movement of the tool support with respect to the sleeve 60.

The block 75 as shown in Figure 6 has an inclined plane undersurface 85, herein shown as being perpendicular to the desired bevel of the pad although it may be at other angles, and as having a knife block 86 adjustably secured thereto. As shown in Figures 6 and 10 a plurality of apertures 87—87 are formed in the bottom of the inclined surface 85, any one of which may receive a pivotal pin 88 extending inwardly from the knife block 86, to form a pivotal support therefor. The knife block 86 has a sector plate 89 formed integrally therewith and abutting the bottom of the inclined surface 85. The sector 89 has an arcuate slot 90 extending therethrough, through which passes a machine screw 91, threaded in the block 75 and adjustably securing said knife block and rotatable knife 14 in position on

the inclined surface 85. It should be noted with reference to Figures 7 and 10, that a plurality of threaded apertures 92—92 enter the block 75 from the inclined surface 85, any one of which may have the machine screw 91 threaded therein, to adjust the rake of the knife 14 with respect to the felt pad being cut, the threaded aperture being used depending upon which aperture 87 the pin 88 is inserted.

The knife block 86, as herein shown, has two spaced bearings 93—93 mounted therein and forming a bearing support for a knife shaft 94, on which a knife 14 is mounted. A collar 95 is secured to the outer end of the shaft 94 to hold said shaft within the bearings 93—93 while a pulley 96 is mounted adjacent the opposite end of said shaft. Said pulley has a hub 97 abutted by the inner face of a knife 14. The knife 14 is secured to said shaft, for rotation therewith, as by a washer and nut 99 threaded on the lower end of said shaft and abutting a hub 100 of said disk knife.

The rotary knife 14 is thus rotatably journaled on the knife block 86 with its periphery inclined at the angle of the desired bevel of the pad and is fed to follow the periphery of the pad during the beveling operation by rotatable movement of the sleeve 60 and by translational movement of the tool support 69 with respect thereto effected by engagement of the cam follower 79 rotating with said tool support with the stationary cam 64, formed to conform to the periphery of the pad being beveled.

The rotary knife 14 is shown in Figures 6 and 10 as being in the form of a disk, the lower face of which is flat and the upper face of which is beveled, sharpening the periphery of the disk to form a sharp rotary knife-like cutting edge. The knife 14 is preferably formed from hardened tool steel, and the angle of the beveled edge thereof may vary, depending upon the angle of the desired bevel of the felt pad, and the types of felt being beveled. A ten degree bevel has been found to be especially suitable for beveling oval pads. Also both sides of the cutter may be beveled if desired.

The drive from the motor 27 to the rotary knife 14 includes a pulley 101 journaled on the sleeve 60 on a bearing 103. A belt 105 connects a motor pulley 106 on a lower end of the motor shaft 28 with the pulley 101, to rotatably drive said pulley. The pulley 101 is herein shown as having a pulley 109 disposed therebeneath and formed integrally therewith and adapted to be engaged by and drive a spring belt 110 made from a closely wound coiled tension spring. The belt 110 has sufficient yieldability to maintain an efficient drive to the pulley 96 and rotary cutter 14 in all positions of translational movement of the tool support 69 with respect to the sleeve 60.

The spring belt 110 extends horizontally from the pulley 109, over direction changing idler pulleys 112—112 and downwardly and inwardly therefrom to and around the pulley 96 on the shaft 94. The direction changing idlers 112—112 are each mounted between the furcations of bifurcated support members 113—113, secured to the upper surface of the flange 61 and projecting outwardly therefrom. The support brackets 113—113 are each inclined at the angle of inclination taken by the belt as it passes from the idlers 112—112 to the pulley 96, and support their respective pulleys at such angles of inclination. A belt guide 114 is mounted on the bottom of the flange 61 as by machine screws 115—115.

The belt guide 114 is herein shown as being of a strap-like formation, made in two overlapping pieces, each of which engages one run of the underside of the belt and maintains sufficient tension on the belt to hold it in engagement with the idlers 112—112 and the driven pulley 96. It will here be noted that the pulley 96 is of relatively small diameter compared with the drive pulley 109, so as to step up the speed of the knife 14 to a higher rate of speed than the speed of rotation of the motor 27.

The drive to the sleeve 60, rotatably feeding the cutter disk 14 in the path of the periphery of the felt pad to be beveled, includes a chain and sprocket drive 116 driven from the upper end of the shaft 28 of the motor 27 through a suitable speed reducer, herein shown as being built into the motor and not shown or described in detail since it may be of any well known form and is no part of my present invention. The chain and sprocket drive 116 serves to drive a transverse worm shaft 117, journaled intermediate its ends in a bearing bracket 118 depending from the support plate 25. A worm 119 on the inner end 25 of the shaft 117 meshes with and drives a worm gear 120 mounted on the sleeve 60 above the pulley 101, and secured to said sleeve as by set screw 121.

A rotatable work supporting table 123 is mounted on the top surface of the base 16 on a vertical spindle 124. The table 123, as herein shown, has a plurality of work carrying mandrels 125 projecting upwardly from its top surface, and shown as being located 90° apart, although they need not be so located. Each of said mandrels has a shouldered upper portion 126 adapted to have a felt corn pad mounted thereon and to hold it in position during the beveling operation. If desired an adhesive or abrasive member may be placed on the shoulder 126, to restrain the pad from rotation, although where the fit of the pad is snug, this is not necessary.

A dog 127, pivotally mounted on the top surface of the base 16 on a pivotal pin 128 is provided to index the table 123 (see Figure 3). The dog 127 is engageable with any one of a plurality of notches 130—130 formed in the periphery of the table 123. An arm 131 projects from the dog 127 to permit disengagement of said dog from the respective notch 130 by hand. A tension spring 132, connected between the table and the lever arm 131, intermediate the ends thereof, is provided to hold the dog 127 in engagement with the required notch.

A depending indexing bar 133 is provided to positively hold the table in position during the beveling operation. Said bar is secured to and depends from a bracket 134, herein shown as projecting outwardly from the support bracket 25. The indexing bar 133 has a reduced lower end portion adapted to register with any one of a plurality of apertures 135—135 formed in the base plate 16, upon lowering movement of the knife 14 into position to bevel the felt pad (see Figures 5 and 6).

In operation of the machine the mandrels 125 may first be loaded with pads, the spring 43 holding the rotary knife 14 to an elevated inoperative position. The table 123 may then be turned until the dog 127 engages a notch 130, indicating that a pad is in the correct position for beveling. The proper cam 64 being mounted on the lower end of the spindle 56 and the proper knife being mounted on the shaft 94, the motor 27 may then be started. At the same time pressure may be

exerted on the pedal of the foot lever 12 by the foot, to engage the indexing bar 133 with the respective aperture 135 and to lower the rapidly rotating and orbitally traveling knife 14 into beveling engagement with the top surface of the felt. Downward movement of the rotary knife 14 and the depth of the bevel is limited by the upper knurled stop nut 32 engaging the lug 34 (see Figure 2). The rapidly rotating knife 14 following the contour of the pad will thus cut the outer edge of the top surface thereof at the desired angle and depth along the entire periphery of the the pad, as shown in Figure 11. When beveling of the first pad is completed, the foot may be released from the pedal of the foot lever 12 to allow the spring 43 to raise the knife 14 out of engagement with the felt. The dog 127 may then be released and the plate 123 turned to position another felt in the proper aligned relation with respect to the beveling knife 14. The dog engaging 15 the proper indentation 131 to index the table 123 until positively held in position by the indexing bar 133, the foot may be engaged with the pedal of foot lever 12 to again bring the indexing bar 133 into engagement with an aperture 135 and bevel the top surface of another felt pad. As one pad is beveled it may be removed from its supporting mandrel during the beveling operation of the next pad and another pad placed on said mandrel, thus affording a substantially continuous beveling 20 operation.

It may be seen from the foregoing that a new and improved method and apparatus has been provided for beveling felt pads by cutting the upper outer surface thereof at an angle by a rapidly rotating knife-like cutter moving transversely of the pad at the angle of the bevel at a high velocity and at the same time, following the contour of the periphery of the pad, making it economically feasible to supply beveled corn or protective pads for use by the general public. It may further be seen that the beveling of the pad is attained due to the high velocity of the inclined knife-like rotating cutter following the contour of the pad, and that the apparatus may be adapted to cut felt pads of various desired contours merely by the substitution of cams having cam surfaces conforming to the contour of the pad to be beveled. It may also be seen that various types of cutters may be substituted to suit various conditions and grades of felt, and that the angle of the knife with respect to the pad may likewise be varied in accordance with the desired bevel of the pad, the shape of the knife used and the softness of the material being beveled. It may further be seen that the apparatus is of a simple and efficient construction, which may readily and safely be operated at high speed production rates by relatively unskilled operators, with no attention from the operator, except to remove and load the pads, and bring the next succeeding pad into position to be beveled.

It may be understood that modifications and variations may be effected without departing from the scope of the novel concepts of the present invention.

I claim as my invention:

1. In an apparatus for beveling felt pads, a frame, a table having a mandrel thereon adapted to support a pad for beveling, a spindle mounted on said frame in vertically spaced relation with respect to said table, a support member journaled on said spindle for movement thereabout, a motor on said frame, a drive connection from said motor to said support member, a tool sup-

port depending from the bottom of said support member and supported and guided thereon for rectilinear movement with respect thereto, a cam and follower interposed between said spindle and tool support, one being stationary and the other being movable about the other, yieldable means holding said cam and follower in engagement with each other and effecting movement of said tool support in a path conforming to the periphery of the pad to be beveled upon rotational movement thereof with respect to said spindle, a rotary knife mounted on said tool support for rotation transversely of the surface of the pad to be beveled and in the plane of the desired bevel of the pad, and a drive connection from said motor to said knife including a member coaxial with said spindle, and a spring belt driving said knife from said coaxial member in all positions of relative movement between said knife and said coaxial member.

2. In an apparatus for beveling felt pads, a frame, a table having a mandrel thereon adapted to support a pad for beveling, a spindle mounted on said frame in vertically spaced relation with respect to said table, a support member journaled on said spindle for movement thereabout, a motor on said frame, a drive connection from said motor to said support member, a tool support depending from the bottom of said support member and supported and guided thereon for rectilinear movement with respect thereto, a cam and follower interposed between said spindle and tool support, one being stationary and the other being orbitally movable thereabout, yieldable means holding said cam and follower in engagement with each other and effecting movement of said tool support in a path conforming to the periphery of the pad to be beveled upon rotational movement of said support member with respect to said spindle, a rotary knife mounted on said tool support for rotation in the plane of the desired bevel of the pad, a pulley journaled for rotation about an axis coaxial with the axis of rotation of said spindle, and rotatably driven thereabout by said motor, a drive connection from said motor to said pulley, another pulley coaxial with the axis of rotation of said knife and disposed at an acute angle with respect to said first pulley for rotatably driving said knife, an extensive spring belt connecting said pulleys in driving and driven relation with respect to each other, and guide means rotatably movable with said support member and guiding said belt from one pulley to the other, to rotatably drive said knife in all positions of relative movement of said knife with respect to said first pulley.

3. In an apparatus for beveling felt pads, a frame, a table having a mandrel thereon adapted to support a pad for beveling, a spindle mounted on said frame in vertically spaced relation with respect to said table, a support member journaled on said spindle for movement thereabout, a motor on said frame, a drive connection from said motor to said support member, a tool support depending from the bottom of said support member and supported and guided thereon for translational movement therealong, a cam and follower interposed between said spindle and tool support, one being stationary and the other being orbitally movable, yieldable means holding said cam and follower in engagement with each other and effecting movement of said tool support in a path conforming to the periphery of the pad to be beveled upon rotational move-

ment of said support member with respect to said spindle, a rotary knife mounted on said tool support for rotation in the plane of the desired bevel of the pad and movable transversely of the face of the pad to be beveled, a drive connection from said motor to said knife for rotatably driving said knife in all positions thereof with respect to said spindle, and operator operated means operatively connected with said tool support for vertically moving said tool support and knife downwardly into engagement with the pad to be beveled and spring means for moving said knife out of engagement with a pad to be beveled upon the release of said operator operated means.

4. In an apparatus for beveling felt pads, a frame, a table adjustably mounted thereon, a plurality of mandrels on said table for supporting the pads for beveling, a support member rotatably mounted on said frame and spaced vertically with respect to said table, a motor on said frame, a drive connection from said motor to said support member, a tool support depending from the bottom of said support member and supported and guided thereon for rectilinear movement with respect thereto, a cam and follower for rectilinearly moving said support with respect to said support member, yieldable means holding said cam and follower in engagement with each other and effecting movement of said tool support in a path conforming to the periphery of the pad to be beveled upon rotational movement of said support member, a rotary knife mounted on said tool support for rotation transversely of the face of the pad to be beveled and in the plane of the desired bevel of the pad, a drive connection from said motor to said knife for rotatably driving said knife in all positions thereof with respect to said spindle, means under control of the operator for vertically moving said tool support and knife downwardly into engagement with the pad to be beveled, spring means disengaging said knife from the beveled pad, and an interengaging connection between said tool support and table engageable upon movement of said cutter downwardly into working engagement with the pad to be beveled, to hold said table and the pad to be beveled in aligned position with respect to said knife.

5. In an apparatus for beveling soft felt pads, a frame, a table adjustably mounted on said frame and having a plurality of mandrels thereon for supporting the pads for beveling, a spindle mounted on said frame above said table, a support rotatably mounted on said spindle, a motor for rotatably driving said support, a tool support depending from the bottom of said support and supported and guided thereon for rectilinear movement with respect thereto, a cam on said spindle and a follower on said tool support for rectilinearly moving said tool support with respect to said table upon rotation of said tool support, a knife rotatably journalled on said tool support for rotation transversely of the face of the pad to be beveled and in the plane of the desired bevel of the pad, extensible drive means for rotatably driving said knife at substantially the

speed of said motor in all relative positions of said knife with respect to said motor, operator operated means for lowering said support and knife into pad beveling position, spring means returning said knife out of pad beveling position, and an indexing bar secured to said support for vertical movement with said knife and having interengagement with said table, to align said table and a mandrel thereon with said knife upon movement of said knife into a pad beveling position.

6. In an apparatus for beveling felt pads, a frame, a table rotatably mounted on said frame, a plurality of mandrels on the top of said table for supporting the pads for beveling, a spindle mounted on said frame, a support rotatably mounted on said spindle and spaced vertically with respect to said table, a motor on said frame, means driven by said motor for rotatably driving said support, a tool support depending from the bottom of said support and supported and guided thereon for rectilinear movement with respect thereto, a cam secured to said spindle, a follower on said tool support engageable with said cam, a spring engaging said follower with said cam, a knife rotatably journalled on said tool support for rotation transversely of the face of the pad to be beveled and in the plane of the desired bevel of the pad, means driving said knife from said motor at substantially the speed thereof comprising a pulley journalled on said tool support for rotation about the axis of said spindle and driving by said motor, an extensible spring belt, a pulley secured to said knife for rotatably driving said knife, means guiding said belt from one pulley to the other, a foot pedal, link and rack means operated by said foot pedal and operatively connected with said support, for lowering said support and knife into pad beveling upon operation of said foot pedal, a spring operatively connected with said foot pedal for raising the knife from said mandrel upon release of foot pressure from said pedal, means indexing said table, and an indexing bar secured to said support for vertical movement with said knife and having interengagement with said table to align said table and a mandrel thereon with a pad to be beveled upon movement of said knife into a pad beveling position.
